Meriwether Lea Morton

UNITED STATES PATENT OFFICE,

WALTER S. MORTON, OF NEW YORK, N. Y.

CONCRETE DAM.

1,001,427.

Specification of Letters Patent. Patented Aug. 22, 1911.

Application filed May 13, 1911. Serial No. 627,035.

To all whom it may concern:

Be it known that I, WALTER S. MORTON, a citizen of the United States, residing in New York city, county and State of New York, 5 have invented new and useful Improvements in Concrete Dams, of which the following is a specification.

My invention relates to improvements in concrete dams, and consists in the features 10 of construction hereinafter described and claimed.

In structures of this character a solid wall dam involves enormous waste of concrete, since the mass is greatly in excess of what is 15 necessary to withstand the pressure of the water upon the deck. So too in less degree there is a large waste of material in the construction of so-called hollow dams, where the deck is supported by solid walls perpendicular to the face of the deck. I have 20 found by careful computation and tests that by means of a properly constructed supporting frame-work great economy in the use of concrete can be achieved and at the same time equal or superior rigidity can be secured in comparison with other types of 25 such structures. I accomplish this by ribs running longitudinally, and in vertical planes across the back of said deck, which 30 ribs are preferably arched, each arch being supported by columns standing approximately perpendicular to the deck. These 35 columns are of graded cross-sectional dimensions with the largest nearer the base of the deck, and are interconnected by braces, preferably at right angles to the columns. By this means the entire load of 40 the water pressure upon the dam is evenly distributed among the several columns and every part of the structure bears its measured and proper load.

In the accompanying drawings, forming part hereof, Figure 1 is a vertical cross section of my improved dam, Fig. 2 is a partial 45 rear elevation of the same, and Fig. 3 a modified detail.

In these drawings, 1 represents a concrete deck having horizontal strengthening ribs 2; 3 ribs or beams lying in vertical planes at 50 right angles to the ribs 2.

4, 5, 6, and 7 are series of bracing columns or supports for the dam. The thickness of the face or floor of the dam is increased downwardly to withstand the increased pressure of the lower strata of water and 55 the columns 4, 5, 6, and 7 are correspondingly heavier the nearer they are placed to the bottom of the dam. 8, 9, 10, 11 and 12 are other series of braces interconnecting the several columns and stiffening the structure as a whole. 13 are arches interconnecting adjacent columns for distributing the load of the deck thereon.

Having thus described my invention, what I claim and desire to secure by Letters 65 Patent is:

1. A dam having an inclined concrete deck, inclined supporting columns therefor standing approximately at right angles to the plane of the deck, said columns being of 70 varying and graduated sizes, the lowermost being nearest the bottom of the dam, braces interconnecting said columns, longitudinally disposed strengthening ribs under said deck, and series of arches arranged between the 75 columns in vertical planes.

2. A concrete dam having an inclined deck, oppositely inclining supporting columns therefor of varying size corresponding to the varying loads upon the deck. 80

3. In a dam, an inclined concrete deck, longitudinally disposed strengthening ribs, arched cross beams in the rear of said deck and concrete supporting columns therefor arranged underneath the arched beams and 85 inclined oppositely to said deck.

4. A dam having an inclined concrete deck, arched strengthening ribs extending longitudinally and in vertical planes on the underside thereof, concrete columns supporting said arches, and lateral braces at right angles to said columns and interconnecting the same. 90

5. In a concrete dam, in combination with the deck thereof, a series of supporting 95 columns graduated in size to correspond substantially with the load upon the different portions of the deck respectively adjacent the said columns.

6. In a concrete dam, in combination with 100

its deck, a series of supporting concrete columns therefor of varying sizes to correspond substantially with the loads upon the respective adjacent portions of the deck, and 5 strengthening and load-distributing ribs upon the rear or bottom face of the deck, as and for the purposes specified.

In witness whereof, I have hereunto set my hand at the city of New York, this 12th day of May, 1911.

WALTER S. MORTON.
